UNITED STATES PATENT OFFICE.

WILLIAM W. HAYS AND EDWARD HAYS, OF MACOMB, ILLINOIS.

DESIGN FOR A POISON-BOTTLE.

47,298.

Specification for Design.

Patented May 4, 1915.

Application filed January 16, 1915. Serial No. 2,764. Term of patent 14 years.

To all whom it may concern:

Be it known that we, WILLIAM W. HAYS and EDWARD HAYS, citizens of the United States, residing at Macomb, in the county of McDonough and State of Illinois, have invented a new, original, and ornamental Design for Poison-Bottles, of which the following is a specification, reference being had to the accompanying drawing, forming a part thereof.

The figure is a perspective view of a poison bottle, showing our new design.

We claim:

The ornamental design for a poison bottle, as shown.

WILLIAM W. HAYS.
EDWARD HAYS.

Witnesses:

M. H. WATSON,
A. W. FALKENTHAL.
